CAMP STOVE

Morton R. Harrison, 3120 E. 28th, Tulsa, Okla.
Filed Nov. 19, 1962, Ser. No. 238,578
2 Claims. (Cl. 126—2)

This invention relates to a camp stove. More particularly, the invention relates to a camp stove utilizing cans of fuels such as jelled alcohol type fuel.

The invention may be described as a camp stove for utilizing jelled alcohol fuel. More particularly, but not by way of limitation, the invention may be described as a camp stove for utilizing cans of jelled alcohol fuel comprising an open top, flat bottomed, shallow container base, an opened top, flat bottomed fuel can container member of a diameter less than said container base and centrally positioned within said container base, said fuel can container member of a diameter to receive a said can of jelled alcohol fuel, a hard setting ballast in the lower portion of said container base surrounding and holding in position said fuel can container, a base cover member closing said container base, said base cover member having an opening therein receiving the upper portion of said fuel can container, said base cover member having grilled support openings therein, a fuel can container member cover removably closing said fuel can container member, said fuel can container member cover having an opening therein, and a removable grill member extending across the said opened top of said fuel can container member, said grill member having integral downwardly extending portions removably received by said grill support openings in said base cover member.

A principal object of the invention is to provide an improved camp stove utilizing jelled alcohol fuel.

More particularly, an object of this invention is to provide a camp stove for utilizing jelled alcohol fuel providing a device having improved heat dissipation means so that the stove itself is heated to a minimum extent by the combustion of the fuel.

Another object of this invention is to provide a camp stove for utilizing jelled alcohol fuel including a simple, inexpensive but sturdy device having improved ballast means to prevent the possibility of it tipping over while in use.

Another object of this invention is to provide a camp stove for utilizing jelled alcohol fuel including a flame control lid member whereby the heat produced by the stove may be controlled and further providing means whereby the stove may be extinguished.

Another object of this invention is to provide a camp stove which utilizes jelled alcohol fuel having two identical units supported to each other in a manner such as to provide an easily handled integral two burner unit.

These and other objects and a better understanding of the invention may be had by referring to the following description and claims, taken in conjunction with the attached drawings in which:

FIGURE 1 is an isometric view of a single unit camp stove of this invention.

FIGURE 2 is an isometric view of a two unit camp stove of this invention with removable portions of one unit of the camp stove shown in exploded arrangement.

FIGURE 3 is an enlarged plan view of one unit of a two unit camp stove according to this invention, as shown looking downwardly upon the top of a stove unit.

FIGURE 4 is a cross-sectional view taken along the line 4—4 of FIGURE 3 showing the internal arrangement of the stove.

FIGURE 5 is a cross sectional view of a portion of the base cover member showing means of supporting the grill.

2

Referring now to the drawings and first to FIGURE 1, a single stove unit is indicated generally by the numeral 10. Stove unit 10 consists basically of an opened top, flat bottomed shallow container base 12, a base cover member 14 closing the upper opening of the base member 12, a fuel can container member cover 16, a pivotally supported flame control lid made up of portions 20A and 20B, a grill 22 and a handle 24. The internal construction and the functioning of the elements of the device will be described in detail subsequently.

FIGURE 2 discloses an embodiment of the invention utilizing two of the stove units 10 which are joined together by a brace member 26 affixed to the base member 12 of each stove unit at the lower portions thereof and a handle member 28 extending between the stove units 10 and connected at each end thereof to the base 12. The handle member 28 is positioned above the brace member 26 in such a way that by grasping the handle member 28 the stove units 10 balance each other and, as will be described subsequently, ballasts in the lower portions of base members 12 of each of the stove units 10 make the complete integral unit of FIGURE 2 easily portable. The dual unit of FIGURE 2 is more or less an optimum embodiment since most occasions for utilizing a camp stove require more than one flame for purposes such as preparing coffee on one of the units while preparing food on the other.

FIGURE 2 shows the grill 22 and the fuel can container member cover 16 removed showing means whereby a can 30 of jelled alcohol fuel may be inserted into the stove unit or the can removed when it is completely burned.

Referring to FIGURE 3, the stove unit is shown in somewhat better detail. Affixed to pivot about pin 32 is 35 the flame control lid 20A. Flame control lid 20A is a flat cover having an integrally formed extending handle portion 20B by which the lid is moved. The lid is shown completely covering opening 34 in the fuel can container member cover 16. In this closed position a flame, if one had previously existed, is extinguished. By dotted outline 40 the lid 20A is shown in a fully open position providing complete exposure of opening 34 allowing maximum flame. Intermediate positions between these two extremes permit various amounts of opening 34 to be exposed to produce varying quantities of flame and therefore varying heat amounts. When the cover member 20A is positioned to cover approximately one-half of the total area of opening 34, then the heat produced by the flame is approximately one-half of the full opening heat.

Referring now to FIGURE 4, a cross-sectional view, the internal arrangement of the device is best shown. An opened top, flat bottomed fuel can container member 36 is centrally supported within the base member 12 and is held in proper position by a quantity of solidified hard setting ballast material 38, concrete, plaster of Paris, or preferably a commercial product known as "Hydrostone," are examples of materials which may be used for ballast 38. In FIGURE 4 a small quantity of the ballast material 38 is shown between the exterior bottom of fuel 55 container member 36 and the interior bottom of base member 12, at 38A. This layer of ballast material 38A serves to insulate against heat transfer to the bottom of the stove unit but, the tendency of the stove to heat at the bottom being not of serious consequence, the preferred arrangement is to position the fuel can container member 36 in direct contact with the interior bottom of base member 12 so that all of the ballast material 38 is in the annulus surrounding container member 36.

In the preferred embodiment as shown, the lower portion 40 of the fuel can container member 36 is tapered inwardly so that a can 30 of jelled alcohol fuel, when

positioned within the stove, is centered, leaving an annulus air space 42 between the can 30 and the interior of the fuel can container member 36. This air space provides insulation to prevent the stove itself from becoming heated as the fuel within can 30 burns.

Affixed to the downwardly extending side of the fuel can container member cover 16 and extending horizontally is a narrow lid support 44 which receives a rivet 32 by which handle portion 20B is pivotally supported.

As can be seen in FIGURES 3 and 4, the integrally formed handle portion 20B of the flame control lid 20A terminates in an upturned portion 46A. The upturned portion is exceedingly handy to remove the lids from containers such as those usually utilized to close jelled fuel cans. When it is desired to open a can of jelled alcohol fuel, the upturned portion 46A of handle 20B is inserted under the lip of the can lid. With a downward motion the lid is pried off. In like manner the end of the lid support 44 is downwardly turned at 46B. The downwardly turned portion 46B may equally be used to pry off can lids. The divergence of portions 46A and 46B facilitates pivoting of the flame control lid.

Grill 22 has integrally formed downwardly extending portions 48 which enter openings 50 in the base cover member 14 by which the grill 22 is removably supported on top of the cooking unit. As shown in FIGURE 5, clips 52 are spot welded to the inner surface of base cover member 14 to limit the extension of the downwardly extending portions 48 within holes 50 so that the grill 22 is supported at a proper height about the cooking unit.

The stove unit of this invention has been described as a camp stove unit, although it is apparent that it has many other applications, such as the use in storm or fallout shelters and for emergency cooking or first aid units and so forth. The camp stove unit of this device is formulated by round containers but it is obvious that containers of various other configurations may be utilized to make up the components of the invention.

The camp stove unit of this invention provides a simple, inexpensive, yet very durable cooking unit formulated in such a way, with ballast 38, so that the device is very difficult to overturn.

The stove is constructed in such a way that good insulation is provided preventing the stove itself from heating during use.

This invention has been described with a certain degree of particularity, but it is manifested that many changes may be made in the details of construction and arrangement of components without departing from the spirit and scope of this disclosure.

What is claimed is:

1. A camp stove for utilizing cans of jelled alcohol fuel or the like, comprising:

- an opened top, flat bottomed, shallow container base; an opened top, flat bottomed, fuel can container member of a diameter less than said container base and centrally positioned within said container base; a hard setting ballast in the lower portion of said container base surrounding and holding in position said fuel can container; a base cover member closing said container base, said base cover member having an opening therein receiving the upper portion of said fuel can container member, said base cover member having grill support openings therein; a fuel can container member cover removably closing said fuel can container member, said fuel can container member cover having an opening therein; a handle affixed to and extending substantially in the plane of the upper surface of said fuel can container member cover; a removable grill member extending across the said open top of said fuel can container member, said grill member having integral downwardly extending portions removably received by said grill support openings in said base cover member; and a flat flame control lid member having an integral handle portion extending therefrom, said integral handle portion pivotally supported to and substantially overlying said handle affixed to said fuel can container member cover, said lid member of a size to fully cover, when in closed position, said opening in said fuel can container member cover.
2. A camp stove according to claim 1 and a second substantially identical camp stove spaced therefrom; a substantially flat brace member affixed at each end thereof to the said container base of each of said camp stoves, said brace member affixed to each of said container bases adjacent the lower exterior portion thereof; a handle member extending between said camp stoves parallel to and spaced above said brace member.
